UNITED STATES PATENT OFFICE

1,928,654

SEAM PRESSING MACHINE

Walter P. Osgood, Malden, Mass., assignor to
Boston Machine Works Company, Lynn, Mass.,
a corporation of Massachusetts

Application February 1, 1932. Serial No. 590,219

12 Claims. (Cl. 69—7)

The present invention relates to seam-pressing machines, and more particularly to that type thereof which is used in the manufacture of men's shoes to press the back seam joining the quarters.

The standard machine of this type is disclosed in the patent to Staples, 1,234,950, July 31, 1917. The Staples seam-pressing machine is provided with a seam-presser and a seam-setter both of 10 which are moved through a four-motion cycle to press the seam, to feed the work and to set the pressed seam. In the Staples machine the seam-presser feeds the work and the setting tool sets the pressed seam at a time when the work is 15 supposed to be stationary, the seam-presser being disengaged from the work. But because the seam-setter is swung rearwardly in contact with the work to rub the stationary seam much of the rubbing action is dissipated owing to the tendency for the seam-setter to feed the work.

The principal object of the present invention is to produce a seam-pressing machine in which the seam is pressed and fed only by the seam-presser notwithstanding that the seam-setter-imparts to the pressed seam a vigorous rubbing action to set it in the position to which it was brought by the seam-presser.

To the accomplishment of this object, and such others as may appear hereinafter, the various 30 features of the present invention reside in certain devices, combinations and arrangements of parts hereinafter described and then pointed out broadly and in detail in the appended claims, possessing advantages readily apparent to those skilled in this art.

The various features of the present invention will be readily understood from an inspection of the accompanying drawing illustrating the best 40 form of the invention at present known to the inventor, in which,

Figure 1 is a view in left side elevation of a seam-pressing machine;

Fig. 2 is a view in sectional elevation on the line 2—2, Fig. 1;

Fig. 3 is a detail view in left side elevation showing the positions the parts adjacent the operating point assume during the initial engagement of the seam-presser with the work;

Fig. 4 is a detail view in sectional plan on the line 4—4, Fig. 1;

Fig. 5 is an enlarged view in perspective of the bottom of the seam-presser or hammer;

Fig. 6 is a detail view in bottom plan showing 55 the normal relationship between the members

of the seam-ridge guide and the salient angle on the seam-presser;

Fig. 7 is a detail view in bottom plan showing the relationship between the members of the seam-ridge guide and the salient angle on the 60 seam-presser when the said members are spread laterally and are moved longitudinally by the seam-ridge inserted between them;

Fig. 8 is a detail view in sectional elevation on the line 8—8, Fig. 3, and

Fig. 9 is a detail view in perspective of the quarters joined together, flesh faces exposed, by a curved line of stitches concentric to their adjacent edges.

The illustrated embodiment of the present invention operates upon a work piece comprising two quarters 10 and 11 (Fig. 9) which are sewed together by a curved line of stitches 12 concentric to the adjacent edges. If the quarters are leather, the faces engaged in Fig. 8 are grain, 70 the flesh faces being exposed. The quarters are opened up (Fig. 8) to present a seam-ridge 13 on one face of the work and a seam-crease 14 on the other face of the work.

In the machine the work is supported upon 80 a roll 15 for the operation of a seam-presser or hammer 16 and a heated seam-setting or rubbing tool 17.

The hammer 16 is provided with a roughened triangular work engaging face 18 (Fig. 5), the salient angle 19 of which is directed towards the front of the machine. The hammer 16 is provided with a cylindrical shank 20 which is secured to the lower end of a link 21 the upper end of which is formed as a strap 22 which embraces an eccentric 23 on a horizontal driving shaft 24 journaled in a frame 25. The link 21 is provided with a slot 26 in which is received a guiding block 27 that is pivoted on a stud 28 (Fig. 2) secured to the frame 25. As a result of this construction the presser 16 has not only a vertical reciprocating movement towards and from the work supporting roll 15, but has also a lateral swinging movement towards and from the back of the machine. Stated in another way, this construction moves the presser 16 100 through a four-motion cycle to engage the work, to feed the work, to leave the work, to return to its original position above the work, and complete the cycle.

The seam-setting or rubbing tool 17 is carried by a bracket 29 projecting rearwardly from a link 30 (Fig. 2) the upper end of which is formed as a strap 31 which embraces the eccentric 23. The link 30 is provided with a slot 32 in which is received a guiding block 33 that is pivoted on 105

a stud 34 secured to the frame 25. As a result of this construction the seam-setting or rubbing tool 17 moves towards and from the work supporting roll 15 simultaneously with the presser 16. The seam-setter 17 also swings laterally towards and from the back of the machine simultaneously with the presser 16. But as the block 33 is pivoted on an axis nearer the eccentric 23 than the axis upon which the block 27 for the presser 16 is pivoted, the lateral swinging movements of the setter 17 are greater in extent than the similar movements of the presser 16 although their cycles are similarly timed. With this construction and mode of operation the presser 16 and the setter 17 engage the work initially simultaneously. The presser 16 then moves rearwardly to feed the work. During this movement of the presser 16 the setter 17 moves rearwardly in contact with the work at a greater peripheral speed than the feed of the work. As the bottom of the presser 16 is roughened to maintain the work under its control, the result of the greater movement of the setter 17 in contact with the work is to rub the seam and set it permanently in the position to which it was brought by the seam-presser 16.

In order to present the seam-ridge properly to the work support 15, the machine is provided with a guide 35 engaged in the seam-crease, a guide 36 embracing the opposite sides of the seam-ridge, and a gage 37 engaging the free end face of the seam-ridge.

The seam-crease guide 35 is secured by a screw 38 carried by the frame of the machine. The free end of the guide 35 terminates close to the work support 15. Near its free end the guide is provided with a horizontal portion having a beveled edge (Fig. 8) for engagement in the seam-crease.

The seam-ridge guide 36 comprises two members 39 and 40 arranged to embrace the opposite sides of the seam-ridge. The members 39 and 40 flare inwardly in the direction the work is fed therethrough. The members 39 and 40 are formed on the lower ends of plates 41 and 42 which are pivoted centrally on the diverging faces 43 and 44, respectively, of a hexagonal surface 45. The upper ends of the plates 41 and 42 engage diverging faces on a second hexagonal surface 46. The front edges of the plates 41 and 42 near their upper ends are engaged by a head 47 on a cylindrical shank 48 mounted on a horizontal pin 49 projecting from the front face on the hexagonal surface 46. The members 39 and 40 are pressed towards each other normally by a spring 50, coiled about the shank 48 and the pin 49 and interposed between the head 47 and a tension-adjusting nut 51 threaded on the free end of the pin 49. The movement of the members 39 and 40 towards each other, under the influence of the spring 50, is limited by a pin 52 projecting laterally from the inside face of the member 39 in position to engage the inside face of the member 40.

The hexagonal surfaces 45 and 46 are formed on the lower end of a rod 53 mounted to slide vertically in bearings 54 formed on a bracket 55 secured to the frame 25. In order to permit the seam-ridge guide 36 to yield vertically the rod 53 is provided with a collar 55. A spring 56 is coiled about the rod 53 and is interposed between collar 55 and the upper bearing 54. The rod 53 near its upper end is provided with a lateral block 57 similar in construction and mode of opera-

tion to the corresponding block disclosed in the patent to Staples hereinbefore referred to. As shown in Fig. 6 the rear ends of the members 39 and 40 extend upon opposite sides of the salient angle 19.

After the quarters are opened up the seam-ridge thereof is introduced between the flaring front ends of the members 39 and 40 of the guide 36. These members converge towards each other so that as the seam-ridge moves rearwardly the members 39 and 40 embrace the opposite sides thereof and confine the sides of the seam-ridge to a predetermined path. At some point in the passage of the seam-ridge through the guide 36, the members 39 and 40, through their frictional engagement with the seam-ridge, are carried with the seam-ridge rearwardly. But as the plates 41 and 42 are pivoted on surfaces diverging rearwardly, forward movement of the members 39 and 40 spreads them apart mutually (Fig. 7). From an inspection of Fig. 7 it is apparent that the thicker the seam-ridge is laterally the further the ends of the members 39 and 40 are positioned rearwardly along the sides of the salient angle 19.

At the same time the sides of the seam-ridge are engaged by the members 39 and 40, the seam-crease and the end face of the seam-ridge are engaged with the guide 35 and the gage 37, respectively (Fig. 8).

The seam-ridge is pushed through the space bounded by the guides 35, 36 and the gage 37 until the leading end of the seam-ridge projects, unsupported from below, beyond the free end of the seam-crease guide. At this point the hammer 16 adjacent the salient angle 19 projecting into the space between the members 39 and 40, which confine laterally the leading end of the seam-ridge, steps upon the unsupported seam-ridge, sets the seam-crease firmly into engagement with the peripheral surface of the work support, and preforms the seam-ridge for the operation of the wider portion of the hammer 16 which rolls the materials of the pieces extending beyond the seam into engagement with the adjacent faces of the quarters.

The setting of the seam-crease, the rolling of the materials of the faces extending beyond the seam and the four-motion feeding movement of the hammer continue until the seam-ridge passes beyond its influence. In the meantime, the portion of the seam-ridge previously operated upon by the hammer is fed beneath the heated tool 17 which gives the seam a vigorous rubbing to set it in the position to which it was brought by the hammer.

Nothing herein explained is to be interpreted as limiting the various features of the present invention in the scope of its application to use in connection with the particular machine or the particular mode of operation or both selected for purposes of illustration and explanation. While the particulars of construction herein set forth are well suited to one mechanical form of the invention and to the use to which it is put, it is not limited to this use, nor to these details of construction, nor to the conjoint use of all its features, nor is it to be understood that these particulars are essential since they may be modified within the skill of the artisan without departing from the true scope of the actual invention, characterizing features of which are set forth in the following claims by the intentional use of generic terms and expressions inclusive of various modifications.
